UNITED STATES PATENT OFFICE.

ALBERT A. PAULY, OF YOUNGSTOWN, OHIO.

APPARATUS FOR FORMING ARTIFICIAL-STONE BUILDING-BLOCKS FROM CONCRETE.

No. 822,013.

Specification of Letters Patent.

Patented May 29, 1906.

Application filed January 22, 1906. Serial No. 297,167.

To all whom it may concern:

Be it known that I, ALBERT A. PAULY, a citizen of the United States of America, residing at Youngstown, in the county of Mahoning and State of Ohio, have invented cer-

5 tain new and useful Improvements in Apparatus for Forming Artificial-Stone Building-Blocks from Concrete, of which the following is a specification, reference being had therein

10 to the accompanying drawings.

This invention relates to certain new and useful improvements in an apparatus for forming artificial-stone building-blocks from concrete or similar suitable plastic material;

15 and the invention relates more particularly to that type of apparatus adapted to produce hollow concrete blocks.

The primary object of this invention is to provide an apparatus of a simple, durable, 20 and effective construction by means of which hollow concrete blocks may be perfectly, rapidly, and cheaply manufactured, the apparatus being adapted to form blocks which may be different in composition as well as design.

25 To this end I have constructed an apparatus consisting of a plurality of elements, such as presses and positive and reliable means for effecting a perfect and substantial concrete building-block.

30 The apparatus as an entirety primarily involves the following elements—namely, a trackway and mold-supporting cars, a plurality of presses arranged above said trackway, a smoothing and polishing device interposed between two of said presses, an endless conveyor and storage or “curing” cars. In this connection the invention resides in the utilization of these elements for quickly forming concrete blocks out of plastic materials, such as sand, cement, or the like substances.

35 The combination of the above-mentioned elements, together with the many details entering into the same, will more readily appear as the nature of the invention is better understood, the same consisting in the novel construction, combination, and arrangement of parts, which will hereinafter be more fully described, illustrated, and claimed.

40 The essential features of the present invention involved in carrying out the objects above specified are in the line of an improvement over my prior applications for patent filed June 24, 1905, Serial No. 266,791, and

45 October 5, 1905, Serial No. 281,483, these applications being for certain useful improve-

ments in concrete-block-forming machines and molds for said machines, the present invention being wholly generic to the above-mentioned applications.

50 Reference will now be had to the drawings accompanying this application, wherein like numerals of reference designate corresponding parts throughout the several views, in which—

55 Figure 1 is a diagrammatic elevation of my improved apparatus, illustrating the same confined within a building in a convenient manner to insure a rapid formation of concrete building-blocks. Fig. 2 is a side elevation of a storage or curing car. Fig. 3 is an end view of the same. Fig. 4 is a side elevation of the presses of the apparatus, illustrating an endless conveyer used in connection therewith. Fig. 5 is a plan of the same. Fig. 6 is a detail side elevation of one of the presses. Fig. 7 is a plan of the same. Fig. 8 is a perspective view of one end of the apparatus, particularly one of the presses. Fig. 9 is a perspective view of a finished concrete block. Fig. 10 is a similar view of the same, illustrating the underneath surface of the block. Fig. 11 is a perspective view of a molding-frame removed from the mold-supporting cars. Fig. 12 is a sectional view of a portion of the apparatus, illustrating the smoothing and polishing device thereof. Fig. 13 is a horizontal sectional view of the same. Fig. 14 is a detail sectional view of a portion of the polishing device. Fig. 15 is a plan of one of the polishers. Fig. 16 is a plan of the polishing device. Fig. 17 is a side elevation of a pallet. Fig. 18 is a vertical sectional view of the same. Fig. 19 is a similar view showing the formation of a block thereon. Fig. 20 is a sectional view of a pallet having a block formation thereon which is being finished by a capping or facing die. Fig. 21 is a perspective view of the capping or polishing die.

60 The apparatus in its entirety is employed for making concrete building-blocks of various sizes and for producing blocks which will have a veneered or polished surface, and by the construction and operation of the apparatus the difficulty of producing in concrete real broken ashlar construction has been solved. The apparatus is preferably located in a building, wherein the concrete or raw product may be thoroughly mixed and easily 65 and quickly conveyed to the apparatus, where it is given the desired form and finish.

and conveyed to a curing or steaming room and then to a storage room or ground. The manipulation of the concrete from the time it leaves the mixing room or compartment of a building involves a process consisting of a plurality of steps, which will be the subject-matter of an accompanying application, the present case simply dealing with the apparatus in its entirety, and in describing the invention in detail the various elements which are combined to one end will be considered in their order, as heretofore mentioned.

Trackway and mold-supporting cars.—In Figs. 1, 6, 8, and 11 of the drawings I have illustrated the trackway and the car which travels upon the same. The trackway is constructed of two beams or girders 1 1, which are arranged parallel with one another and support rails 2 2. Upon the rails 2 2 is adapted to travel a car embodying a platform 3, supported upon trucks 4 4. Upon the platform 3 is mounted a framework consisting of longitudinally-arranged bars 5 5 and transversely-arranged bars 6 6. Journalized in the protruding ends of the bars 5 5 are rods 7 7, while journalized between the protruding ends of the bars 6 6 are rods 8 8. Mounted upon the rods 7 7 are end doors or gates 9 9, while side doors or gates 10 10 are mounted upon the rods 8 8. These doors or gates when folded upwardly are adapted to form a substantially rectangular molding-frame, which may be divided and subdivided into a plurality of compartments, the number of these compartments depending entirely upon the number and size of concrete blocks to be made at one operation. In the present instance I have illustrated a molding-frame in Fig. 11, wherein the frame formed by the side gates 10 10 and end gates 9 9 is subdivided into four compartments 11, the inner walls of said compartments being formed by supplementary side gates 12 12, hinged centrally of the framework supported by the car, and by supplementary end gates 14 14, also hinged to the framework of the car. In order that the various gates of the car will properly interlock and support one another while the concrete is being subjected to pressure, I provide the end gates 9 9 and 14 14 with outwardly-extending lugs 15 upon their ends, said lugs being engaged within the recesses 16, carried by the upper edges of the side gates 10 10 and 12 12. To further lock the gates in a vertical position, I provide the side gates 10 10 and 12 12 with transversely-alining notches or recesses 17, and in these notches or recesses is adapted to engage a bar 18, having depending ends 19 19, said ends being adapted to engage the outer sides of the gates 10 10 and firmly hold said sides in engagement with the end gates 9 9 and 14 14. The construction of the "gates" or "side walls," as they may be termed, of the molding-frame permits of the frame being easily and quickly opened after

the concrete has been formed therein, as will be hereinafter more fully described.

In connection with the rectangular molding-frame as carried by the platform 3 of the car I use pallets 20, (see Fig. 17,) a pallet being used in each one of the compartments 11 of the molding-frame. The pallets are preferably constructed of wood, and besides a foundation-plate 21 they constitute a core 22, said core having tapering walls, whereby when the concrete block has been formed the pallet can be easily and quickly removed without disfiguring the block. The depth of the pallets is regulated according to the depth of the gates used in connection with the molding-frame of the car, said pallets in practice being of a less depth than that of the gates or side walls of the molding-frame to permit of the front or bearing wall 23 of a block being formed, as will hereinafter appear. 75 80 85

Presses.—Parallel with each side of the trackway just described and upon the outer sides thereof I arrange beams 24 24, which support the presses 25, 26, and 27 (see Fig. 4) of the apparatus, the press 25 being used in the first formation of the block to give it its initial pressure, the press 26 subjecting the refilling to a pressure and capping or veneering of the same, while the press 27 is used as an auxiliary press in case it is desired to further subject the blocks to pressure. Each one of the presses is identical in construction with the exception that the dies of said presses are changeable, a slight difference also residing in connection with the press 25. Each press is formed of four standards or columns 28 28 and 29 29, the upper ends of said standards or columns being connected together by side rails 30 30 and transverse rails 31 31. The side rails 30 30 are recessed, as at 32, to accommodate journal-boxes 33 33, in which are journaled transversely-arranged shafts 34, 34, and 35. Centrally of the shafts 34 34 are mounted large gear-wheels 36 36, which are adapted to mesh with a small gear-wheel 37, mounted upon the shaft 35, said shaft serving functionally as a drive-shaft and being driven through the medium of a belt-pulley 38, mounted upon the protruding end of the shaft 35, the rotary motion imparted to the shaft 35 from the belt or pulley wheel 38 being governed by a conventional form of clutch mechanism 39. At this point it is well to state that I do not care to confine myself specifically to the power employed for operating my improved presses, as the drive-shaft 35 of each press may be independently driven and controlled by a motor or all the shafts may be connected together by belts or sprocket-chains and operated from a common source of energy, the independent operation of each press being controlled by the clutch mechanism 39.

Mounted upon the shafts 34 34 at each side of the large gear-wheels 36 are eccentric 130.

trics 40 40, said eccentrics carrying hangers 41, which are connected to a rectangular frame 42, said frame being slidably mounted between the standards or columns 28 28 and 5 29 29, the frame being guided in its movement by plates 43 43, which protrude between the standards or columns 28 28 and 29 29. The frame 42 carries a die-housing 44, in which a plurality of dies 45 are mounted.

10 The dies used in connection with the press 25 are simply pressure-dies which are adapted to engage the concrete within the molding-frame of the car and subject the same to pressure, while the dies of the press 26 may be of such a form as to give the front or bearing wall a desired configuration and finish.

15 The columns or standards 28 28 of the press 25 are provided with a transverse stripper-bar 46, the object of which will presently 20 appear.

Smoothing and polishing device.—Between the presses 26 and 27 I arrange a smoothing and polishing device which is adapted to veneer and finish the concrete blocks and remove all imperfections in the surface of the front or bearing wall of a concrete block. The device is constructed of a framework 47, consisting of two transverse bars 48 48, having screw-threaded openings 49 in their ends. 25 Extending through the openings 49 of the bars 48 are vertically-disposed screws 50, which are revolvably mounted in brackets 51 51, carried by the presses 26 and 27, it being understood that two brackets are carried by each press. The revoluble screws 50 are provided with nuts 52, whereby they can be easily rotated to raise or lower the bars 48 48. The bars are connected together by longitudinally-disposed girders 53 53, and revolvably mounted in each girder are two sleeves 54 54, through which pass shafts 55 55, said shafts being substantially rectangular in cross-section and adjustably held in engagement with the revoluble sleeves 54 54 by set-screws 56 56. Upon the lower ends of the shafts 55 55 are eccentrically-mounted polishers 57 57, these polishers being adapted to engage the front or bearing wall of a concrete block and polish the same. Slidably mounted 30 upon the upper ends of the shafts 55 are gear-wheels 58 58, said wheels being adapted to mesh with a common gear-wheel 59, revolvably mounted centrally of the frame 47 upon a transverse support 60. The common gear-wheel 59 is provided with a beveled gear 61, meshing with a beveled gear 62, mounted upon a shaft 63, journaled in a bearing 64, carried by one of the girders 53. The outer end of the shaft 63 is provided with a belt 35 pulley or wheel 65, whereby the smoothing and polishing device may be driven similar to the presses 25, 26, and 27, heretofore described. Reciprocating polishers may be used in lieu of rotary polishers.

40 *Endless conveyers.*—The conveyer which I employ in connection with my improved apparatus is arranged from one end of the apparatus to the other and is adapted to travel from the press 27 to the press 25, whereby when the pallets 20 are removed from the 45 molding-frame of the car they can be immediately returned to the press 25, the conveyer also serving to carry defective blocks to the press 25, where they may be re-pressed or worked over again. The conveyer is constructed within a pit 66, preferably at one side of the apparatus, and the conveyer comprises a drive-wheel 67, a wheel 68 at the opposite end of the pit, and a plurality of idlers or chain-supporting rollers 69, over which an 50 endless chain or conveyer 70 is adapted to travel. The drive-wheel 67 may be driven by a motor or may, as illustrated in Fig. 1 of the drawings, be driven from the press 27 through the medium of a sprocket-chain 71, 55 a sprocket-wheel 72, and a chain 73. I do not care to confine myself to the type of conveyer used or to its specific use, as in some instances it can be readily dispensed with.

Storage and curing cars.—After the concrete blocks have been properly formed by the presses they are seasoned or, as known to the trade, "cured," in order that the artificial stone may have sufficient waterproof qualifications for all practical purposes. In this 60 connection I construct a track 74 adjacent to the trackway previously described, preferably at the end of the trackway adjacent to the press 27. The track 74 is adapted to lead to a suitable building where my improved storage or wet-stone cars may be placed until the concrete blocks carried by them have been properly seasoned and cured. One of the cars which I employ is illustrated in Figs. 1, 2, and 3 of the drawings and consists of a box-like structure 75, mounted upon a truck 76. The box-like structure is provided with two side doors 77 77, which are hinged at the top edges of the car and swing outwardly, as clearly illustrated in 65 Fig. 3, and when in this position are supported by angularly-disposed bars 78 78, whereby easy access may be had to the interior of the box-like structure. Within the box-like structure is constructed a skeleton 79 to support the concrete blocks. 70

Each car carries a central depending steam-inlet pipe 80, above which is located a deflector 81. After the cars loaded with concrete 75 blocks have been removed to a suitable compartment or building steam-supplying pipes are connected to the pipes 80 of each car, and as the doors 77 are closed the contents of each car will be subjected to a thorough 75 steaming, which tends to render the blocks waterproof, especially after they have been so treated for a period of time, and then removed to thoroughly dry out. The cars are 80 preferably constructed of strong and dura-

ble material, whereby they will withstand the load to which they are subjected, also the action of steam while the blocks are being seasoned or cured.

5 The detail construction of the entire apparatus having been described, the preferable manner of operating the same is as follows, reference being had particularly to Fig. 1 of the drawings: As heretofore stated, the apparatus is preferably mounted in a building wherein the concrete is mixed, and in practice I have found it convenient to mix the concrete upon the floor above the apparatus and convey it to said apparatus through chutes 82 82', the outlets of which are controlled by gates 83 83, whereby a workman may permit a certain quantity of concrete to descend—for instance, a quantity that would fill the molding-frame of the concrete, which is located beneath the chute 82. The desired pallets having been selected and positioned within the molding-frame of the car, the thoroughly-mixed concrete is admitted to the car, after which the car is moved forwardly beneath the press 25. The car in its movement travels beneath the stripper-bar 46, which is adapted to remove the excess concrete carried by the molding-frame. After the car has been positioned beneath the press 25 the clutch mechanism 39, or the motor which operates the shaft 35 of said press, is thrown into operation, and as the frame 42 descends and engages the concrete the dies 45 45, carried by the frame 42, subject the concrete to a pressure which forms the same, as shown in Fig. 8 of the drawings, wherein the gates of the molding-frame are thrown open and the dies elevated to illustrate the configuration of the concrete blocks after their initial pressure. As the surface of the blocks now lie below the top edges of the molding-frame and in close proximity to the top surface of the pallets the car is moved forward between the presses 25 and 26, where it is refilled from the chute 82'. The refill forms what I have termed the "front" or "bearing" wall 23 of a concrete block, which was the subject-matter of one of the above-mentioned applications. The car is now moved beneath the press 26, and I will assume that the frame 42 of said press is provided with dies 84 84, adapted to produce beveled edges 85 85 upon the bearing-wall 23 of the concrete block. The press 26 is now thrown into operation to subject the refilling to a pressure which produces a surface upon the block. (Shown in Fig. 9 of the drawings.) The car is now moved forward beneath the smoothing or veneering device, the polishers 57 57 of which have been previously adjusted relative to the gear-wheels 58. After the car has been moved beneath the device the screws 50 are rotated to move the polishers gradually into engagement with the concrete

blocks, and when the device is thrown into 65 operation the eccentrically-mounted polishers are adapted to smooth and veneer the upper surface of the concrete blocks. Heretofore the veneering and smoothing of concrete blocks have been manually accomplished, 70 while I automatically accomplish the same through the medium of my improved device, and it is in this connection that I do not care to confine myself to the specific construction of the device shown, as slight modifications 75 may be made therein for accomplishing practically the same result. After the blocks have been polished or veneered the cars are moved to or through the press 27, this press simply being used as an auxiliary press in 80 case it is desired to double the capacity of my improved apparatus, which could be accomplished by using two cars and another smoothing and veneering device, which would be located between the presses 25 and 85 26. When the car has reached the end of the main trackway of the apparatus, the gates thereof are thrown open and the pallets placed in the storage and curing cars 75, the pallets and their respective concrete blocks 90 being placed upon the shelves 79 of the cars. The car when loaded is closed and transferred to another compartment, where its contents are seasoned and cured; after which the car is transferred to a storage room or ground 95 and the blocks removed, the car then being returned to the apparatus with the empty pallets, which are removed and placed upon the endless conveyer or chain 70 of the apparatus and returned to the press 25, where the 100 pallets may again be used.

From the foregoing description of the construction and operation of my improved apparatus it will be observed that I have devised novel means for expeditiously forming 105 concrete blocks, and while I have herein illustrated the preferred manner of accomplishing the same I do not care to be confined to the minor details of construction, such as the shape of the pallets and dies or the manner in which the mechanism of my improved apparatus is driven, and such changes as are permissible by the appended claims may be resorted to without departing from the spirit and scope of the invention.

115 What I claim, and desire to secure by Letters Patent, is—

1. In an apparatus, the combination of a trackway, a plurality of presses erected above said trackway, a car adapted to travel upon said trackway beneath said presses; a molding-frame carried by said car and comprising hinged gates, detachable dies carried by said presses, a polishing device mounted between said presses above said trackway, said polishing device consisting of a plurality of rotary polishers, an endless conveyer mounted adjacent to said presses, means to vertically

reciprocate said dies, means to revolve said polishers, and means to simultaneously operate said conveyer, substantially as described.

2. An apparatus of the type described embodying a trackway, a car mounted upon said trackway, a molding-frame carried by said car and consisting of a plurality of interlocking gates, presses mounted above said trackway, vertically-reciprocating interchangeable dies carried by said presses, a polishing device mounted between two of said presses, and means to simultaneously operate and independently control said presses and said polishing device, substantially as described.

15 3. An apparatus of the type described embodying a plurality of presses, a movable car located beneath said presses, a molding-frame carried by said car and adapted to receive concrete, pallets mounted in said molding-frame, vertically-reciprocating dies carried by said presses and adapted to engage said concrete, an adjustable polishing device mounted between two of said presses, means to operate said presses, means to operate said polishing device, means to strip said molding-frame, substantially as described.

20 4. An apparatus of the type described embodying a plurality of presses, a movable car located beneath said presses, a molding-frame carried by said car, vertically-reciprocating detachable dies carried by said presses, an adjustable polishing device supported between two of said presses, means to operate said presses, and means to operate said polishing device, substantially as described.

25 5. In an apparatus, the combination with a trackway, of a car mounted upon said trackway, a molding-frame carried by said car, interlocking gates hinged to said frame, pallets mounted in said frame, presses mounted above said trackway, a plurality of detachable dies carried by said presses, a polishing device supported between two of said presses, revoluble polishers adjustably carried by said device, an endless conveyer mounted adjacent to said presses, means to strip said molding-frame, means to operate said presses, means to operate said polishing device, means to operate said conveyer, and means to independently control said presses, said device and said conveyer, substantially as described.

30 6. In an apparatus, the combination with a trackway and a car mounted thereon, of a molding-frame carried by said car, interlocking gates hinged to said frame, pallets mounted in said frame, a plurality of presses mounted above said trackway, vertically-reciprocating dies detachably carried by said presses, a polishing device supported between two of said presses, means to reciprocate said dies, and means to operate said polishing device, substantially as described.

35 7. In an apparatus, the combination with a molding-frame, interlocking gates carried

by said frame, pallets supported by said frame, of a plurality of presses, vertically-reciprocating dies detachably carried by said presses, a polishing device mounted between two of said presses, means to operate said presses, means to operate said device, and means to move said molding-frame beneath said presses and said device, substantially as described.

8. In an apparatus, the combination of a molding-frame, pallets carried by said frame, a plurality of presses, detachable dies carried by said presses, a polishing device mounted between two of said presses, means to vertically reciprocate said dies, means to operate said device, and means to move said molding-frame beneath said dies and said polishing device, substantially as described.

9. In an apparatus, the combination with a trackway and a car mounted thereon, of a molding-frame carried by said car and adapted to receive concrete, interlocking gates hinged to said frame, pallets carried by said frame, means to strip said frame, means to lock said gates, means to subject the concrete in said frame to an initial pressure and a refilling pressure, and means to smooth and polish the concrete in said frame, substantially as described.

10. In an apparatus, the combination with a trackway and a car, of a molding-frame carried by said car and adapted to receive concrete, interlocking side gates and end gates carried by said frame, supplementary side gates and supplementary end gates mounted within the first-named side gate and end gates, pallets carried by said frame, means to strip said frame, means to subject the concrete of said frame to pressure, substantially as described.

105 11. In an apparatus, the combination with a trackway and a car, of a molding-frame adapted to receive concrete, interlocking side gates and end gates carried by said frame, supplementary side gates and supplementary end gates mounted within and interlocked with the first-named gates, means to strip said frame, means to subject the concrete of said frame to pressure, substantially as described.

110 12. In an apparatus, the combination with a trackway and a car, of a molding-frame carried by said car, presses mounted above said trackway, movable dies carried by said presses, a polishing device supported between two of said presses, a conveyer arranged adjacent to said trackway, means to operate said presses, means to operate said polishing device, and means to operate said conveyer, substantially as described.

115 125 13. An apparatus of the type described embodying a plurality of presses, detachable dies carried by said presses, a movable molding-frame adapted to travel beneath said dies, means to vertically reciprocate said dies,

and means to move said frame, substantially as described.

14. An apparatus of the type described embodying a plurality of presses, dies carried by said presses, a molding-frame, a polishing device interposed between said presses, means to move said molding-frame beneath said presses and said polishing device, and means to independently operate said presses and said polishing device, substantially as described.

15. An apparatus of the type described embodying a plurality of vertically-reciprocating dies, a movable molding-frame adapted to travel beneath said dies, a polishing device mounted adjacent to said dies, and means to independently operate said dies and said polishing device, substantially as described.

16. An apparatus embodying a plurality of sets of vertically-reciprocating dies, a molding-frame, and means to move said frame from one set of dies to another set of dies, substantially as described.

17. An apparatus consisting of a polishing device, a molding-frame adapted to contain concrete, means to subject the concrete of said frame to pressure, and means to move said frame to meet said polishing device to be polished thereby, substantially as described.

18. An apparatus consisting of a molding-frame, presses, a polishing device, a conveyor, and means for simultaneously operating the presses and polishing device substantially as and for the purpose described.

19. An apparatus consisting of a molding-frame, presses, a polishing device, and means for simultaneously operating the presses and polishing device substantially as and for the purpose described.

In testimony whereof I affix my signature in the presence of two witnesses.

ALBERT A. PAULY.
